UNITED STATES PATENT OFFICE.

VINCENT J. GILMORE, OF WAPPINGERS FALLS, NEW YORK, ASSIGNOR TO THE DE LAVAL SEPARATOR COMPANY, OF NEW YORK, N. Y., A CORPORATION OF NEW JERSEY.

CENTRIFUGAL-SEPARATOR FEEDING DEVICE.

Application filed May 19, 1927. Serial No. 192,611.

My invention relates to faucets for supplying milk (or other liquid) to centrifugal separator bowls.

To facilitate handling, certain centrifugal separators are provided with a support, above the machine frame, on which rests a supply can containing the liquid to be fed to the separator bowl, the supply can being provided with a discharge faucet and being turnable in a horizontal plane into and out of position to bring its faucet directly above the bowl and its covers and into feeding relation with the regulating cup on the covers. Of necessity, therefore, the faucet outlet must be higher than the top of the regulating cup. However, the best operation requires that the faucet, when in operative position and delivering liquid to the regulating cup, shall be lower than the top of the cup so as to be relatively close to the float valve therein and thereby avoid splashing and surging.

The object of my invention is to allow the supply can to be turned in a horizontal plane and have its faucet, when closed, clear the regulating cup and to automatically position the faucet outlet below the top of the regulating cup when, after being operatively positioned, it is opened to allow outflow of liquid into the regulating cup.

The invention comprises a faucet so constructed that its opening movement involves a bodily displacement of the outlet end of the faucet from a higher level (above the top of the regulating cup) to a lower level (below the top of the regulating cup).

A preferred embodiment of the invention is shown in the accompanying drawings, in which—

Fig. 1 is a side view of a centrifugal separator equipped with a structure embodying my invention.

Fig. 2 is a detail sectional view of the faucet associated with the regulating cup.

Fig. 3 is a side view of the same, showing the faucet closed.

On the frame *a* of the separator is an elevated platform *b* on which is supported a supply can *c* turnable in a horizontal plane to bring its faucet into and out of the liquid delivery position, illustrated in Fig. 1, above the regulating cup *d*, which is mounted on covers *e* for receiving the separated liquids discharged from the bowl.

The faucet comprises a body *f* having a feed passage *g* and a tapered socket *i*, the

feed passage communicating at opposite ends with the supply can and the socket. Within the socket is a turnable tapered faucet plug *h* provided with a handle *j*. The socket is so positioned that the axis of the plug extends at an oblique angle to the vertical. The plug *h* is provided with an outlet tube *k* whose axis extends vertically when the plug is turned into position to cause the tube *k* to register with passage *g*, as shown in full lines in Fig. 2, and is displaced more or less toward a horizontal position when the plug is turned into position to close communication between tube *k* and passage *g*, as shown in Fig. 3 and in dotted lines in Fig. 2. In the embodiment shown, the axis *x* of the plug is at the same angle to the vertical as the axis *y* of the outlet tube *k* is to the axis of the plug.

By so constructing the plug that its discharge tube is bodily swung down into a vertical position when the faucet is opened and is bodily swung up toward a horizontal position when the faucet is closed, it is possible to have the closed faucet clear the top of the regulating cup when the supply can is turned in a horizontal plane into, or away from, liquid delivery position and to have the discharge end of the faucet at the desired level below the top of the regulating cup when the supply can is in delivery position and the faucet opened.

Having now fully described my invention, what I claim and desire to protect by Letters Patent is:

1. The combination with a centrifugal separator, a supply can positioned thereon and a separating bowl and its regulating cup, of a faucet controlling the flow from the supply can to the regulating cup; said faucet comprising a turnable member movable into two positions, one to open the faucet and simultaneously lower its outlet to below the level of the top of the regulating cup, and the other to close the faucet and simultaneously raise its outlet to above the level of the top of the regulating cup to permit the supply can to be freely turned in a horizontal plane.

2. The combination with a centrifugal separator, a supply can positioned thereon and a separating bowl and its regulating cup, of a faucet controlling the flow from the supply can to the regulating cup; said faucet comprising a faucet body having a feed passage communicating with the supply can and a

member, having a feed passage and turnable into one position on the faucet body to connect the two feed passages and position the outlet from the second passage below the 5 level of the top of the regulating cup and movable into another position on the faucet body to disconnect the two feed passages and position the outlet from the second passage at 10 a level above that of the top of the regulating cup.

3. The combination with a supply can for a centrifugal separator, of a faucet comprising a faucet body having a tubular feed passage communicating with the interior of the supply can and a plug socket beyond the end of the passage, and a plug turnable in said socket on an axis oblique to the vertical and having a feed passage which assumes a substantially vertical position with its outlet end at a 15 relatively low level when the plug is turned into position to open communication between 20 said passages and which assumes a position

at an angle to the vertical with its outlet end at a relatively high level when the plug is turned into position to close communication 25 between said passages.

4. The combination with a supply can for a centrifugal separator, of a faucet comprising a faucet body having a substantially horizontal feed passage communicating with the interior of the supply can and a plug socket beyond the end of the passage, and a plug turnable in said socket and having an outlet tube which, in the turning movement of the plug, may be brought into and out of register 30 with the feed passage in the faucet body, the axis of rotation of the plug being at an oblique angle to the vertical and the axis of its outlet tube being at the same angle to the 35 axis of rotation of the plug.

In testimony of which invention, I have hereunto set my hand, at Poughkeepsie, N. Y., on this 16th day of May, 1927.

VINCENT J. GILMORE.
